FRANK HENRY SLEEPER, OF WORCESTER, MASSACHUSETTS, ASSIGNOR TO SLEEPER & HARTLEY, INC., OF WORCESTER, MASSACHUSETTS, A CORPORATION OF MASSACHUSETTS.

AUTOMATIC STRAIGHTENING-MACHINE.

1,221,384.

Specification of Letters Patent.

Patented Apr. 3, 1917.

Application filed January 15, 1914. Serial No. 812,247.

To all whom it may concern:

Be it known that I, FRANK HENRY SLEEPER, a citizen of the Dominion of Canada, and a resident of Worcester, county of 5 Worcester, and State of Massachusetts, have invented a new and useful Improvement in Automatic Straightening-Machines, of which the following is a specification.

My invention relates to machines of the 10 class used for the straightening of round rods, shafting, pipe or tubing, and the object of my invention is to provide a machine so designed and constructed that such rods, shafting, or tubing may be automatically 15 fed therethrough, and automatically straightened therein to a very high degree of accuracy, without injuring the material or marring the surface thereof.

A further object of my invention is to 20 provide a machine capable of handling material within a wide range of different diametral sizes, by merely making certain simple substitutions in some essential parts of the machine, as will be hereinafter described.

A further object of my invention is to 25 provide a machine in which very short lengths of material may be very accurately straightened.

In illustrating my invention I have shown 30 one of the simpler forms in which I have put this invention into practice,—consisting of a single reciprocable die, mounted for transverse movement within a head which 35 is rotatable within a series of rollers revolving thereabout. This movable die is reciprocated toward the center of rotation by any one of the series of rollers, as the head rotates and as the die is brought into contact 40 successively with each roller which it overtakes in its rotation; and is moved away from the center by centrifugal force between each such contact period.

Outside of the frame inclosing the die 45 head, and in close proximity thereto, two sets of positively driven feed rolls are mounted, by means of which the material to be straightened is fed through the center of the rotatable die head described above,

and past the reciprocable straightening die. 50 In the operation of the machine, the object to be straightened is first entered between a pair of feeding rolls, and is thereby fed forward into the straightening head, the various members being so designed and mounted that, as the latter rotates, the movable die therein contacts at predetermined intervals with a portion of the outer circumference of the material bending the object out of axial alinement. The die is retracted by centrifugal force as the head rotates,—the material being meanwhile fed steadily forward at a predetermined rate,—until the next roll is encountered, when the returning die again presses the object out 60 of line, this process being repeated continuously until the entire length of the straightened object finally emerges from the farther feed rolls.

It will be obvious that the path of the 70 straightening die about the circumference of the object is a spiral of more or less constant pitch, and that the essentials of my invention consist in providing a straightening device operating with successive 75 movements about the object to be straightened in such a manner as to successively bend portions of it away from a fixed center into a spiral path, with the result that the object thus acted upon acquires a true, 80 straight appearance, so far as can be measured with the ordinary instruments of precision in practical use.

While I have here illustrated and described one of the preferred forms of my 85 invention, I desire it to be understood that I do not restrict myself to the precise mechanical forms and terms in which I have illustrated and described my invention, since it is manifest that such may be very 90 widely varied by the skilled designer without departing from the essentials of my invention, and without obtaining any material change in the result produced.

I believe myself to be the first to apply 95 such a method of straightening to material of circular section, and the first to devise an automatic machine of simple and practical

form in which this invention is embodied, and I therefore claim this invention broadly in its various equivalent forms.

Referring to the drawings:

5 Figure 1 represents a plan view of the straightening mechanism with the feeding devices.

Fig. 2 represents a vertical elevation of the same, looking from the left hand side 10 of the machine.

Fig. 3 represents a front elevation of the machine, and

Fig. 4 represents a sectional elevation of the same, taken on the line 4, 4 of Fig. 3, looking 15 in the direction indicated.

Fig. 5 represents a view of the rotating members viewed from the front, with the feed devices and exterior plate removed.

Fig. 6 represents the die hammer, and 20 Fig. 7 represents the straightening die, both drawn perspectively.

Referring to Figs. 3, 4 and 5, the body enclosing the straightening members is designated by the numeral 1, and is shown as consisting of a substantial frame, preferably of 25 cast iron, secured in any suitable manner to a base or support such as the table 2.

The rotating die head 3, suitably formed from steel or other durable metal, is mounted 30 for rotation within the head 1, the latter being formed and recessed in one of its vertical faces to receive it.

The die-head 3 may be driven by any suitable means. In the form shown herewith, 35 I make use of the pulley 4, mounted upon one end of the hollow shaft 5, to the opposite end of which the die-head 3 is fastened, the shaft being intermediately supported for rotation in the frame 1. An enlarged portion 40 6 is formed upon the head 3, and the frame 1 is suitably recessed to contain a series of bearing rolls 7, preferably made of steel, hardened, and mounted upon bearing pins 8, the latter being suitably spaced in 45 the annular bearing cage members 9, 9, so that the whole roller bearing member incloses circumferentially the part 6 of the head 3, and acts in a manner as an anti-friction bearing for it.

50 A circular opening is formed so as to extend axially through the die-head 3, one end of the hollow shaft 5 being inclosed and permanently mounted therein in any desired manner, while in the opposite or front end

55 of the head a rectangular opening 10 is formed, from the outer circumference of the enlarged part 6 inward, as shown in Figs. 4 and 5. In this opening 10 the straightening die 11, and the die-hammer 12 are

60 mounted for reciprocal movement. These members are preferably made of steel, hardened. To retain the hammer 12 in the head 3 against the centrifugal force exerted during rotation, it is formed with transverse projections or shoulders 13, 13, adapt-

ed to enter coöperating recesses 14, 14, in the head, and thus limit the movements of the die hammer.

The die member 11 is so formed as to partly inclose the object to be straightened; 70 is flared at each end so as to permit the easy admission of objects to be straightened: and is made of different materials, such as soft metals, rubber, fiber, &c., according to the material to be acted upon.

75 As the head 3 rotates, carrying with it the die 11, and the die hammer 12, these parts tend to move centrifugally outward into the space between adjacent rollers 7, freeing the die 11 from the object to be straightened, 80 designated as 15: and, as the hammer 12 encounters the next roller it is again driven in, forcing the die 11 inward against the object 15 and bending the latter out of axial alignment.

85 A substantial metal plate 16 conforming in appearance to the frame 1, is mounted upon the latter in such a manner as to cover the front of the same, and so as to inclose and retain the rotating head 3, and the roller bearing cage 9, in operative position. This plate 16 may be secured in any suitable way to the frame, and is provided with a central opening in which is mounted a hardened steel sleeve or guide bushing 17, having an 90 opening therethrough in an axial direction to permit the passage of the object 15. A similar bushing 18, is mounted axially in the rotating head 3, and is similarly perforated for the same purpose.

100 The object 15, (indicated in this case as a tube) is fed through the machine by means of the pairs of feed rolls 19, 19 and 20, 20. These rolls are suitably mounted in pairs in the frames 21, 21 for rotation, the shafts of 105 each pair being geared together, and the two sets of rolls being driven in approximate synchronism by any suitable method; such, for instance, as the worm and worm gear 22, 23, shown in Fig. 2.

110 To prevent undue wear, all the parts which come in contact with the object may be made of any very durable material, such as steel, hardened.

The rolls 7 are also made preferably of 115 similar material, and I further provide in the frame 1, a ring or raceway 24, of suitable width and made of hardened steel, for these rolls to run upon.

120 The operation of the machine may be briefly described as follows: Referring to Fig. 4, the end of the object 15, pushed between the feed rolls 19, 19, is gripped thereby and is fed through the fixed bushing 17, and past the die member 11, which partly encircles it during the bending operation. The head 3 is meanwhile being rotated at the desired speed, and, as this head 3 rotates, carrying the die and hammer members 11 and 12 with it, these latter are alternately 130

driven toward and from the axis of rotation as the hammer 12 strikes the rolls 7, and as the centrifugal force of rotation frees the die from the tube and carries it outward for 5 the next blow, which occurs as the hammer strikes the next roll. The die 11 being carried in a rotating member, its movement takes effect in a spiral path about the object 15, as the latter is fed at a predetermined 10 rate through the machine. At first the end only of the object 15 is bent, but as it progresses it encounters and enters the guide bushing 18, and the bending action by means of which the object acquires its straight 15 appearance, thereafter takes place between these two relatively fixed points,—the guide bushings 17 and 18—until the opposite end of the object has arrived at the bending point, and is thereafter supported in the 20 guide bushing 18 only until it finally emerges from the machine. It has been found in practice that by this method of treating objects of circular section they are made to appear extremely true and straight 25 from end to end.

In order that dust or scale may be prevented from passing the die member 11 into the interior of the machine so as to clog the same, I provide the straightening die 11 with 30 an encircling groove 25, and fill this groove with felt of a suitable quality. The felt acts as a wiper, preventing the passage of any foreign particles into the bearings of the machine.

35 To further provide for the speedy removal of such particles of grit or dust from the machine, I provide in the head 3 a series of inclined openings 26, and further provide the exterior plate 16, with an opening 27, so that any dust which is generated in the 40 center of the mechanism may fall freely along the grooves 26, and through the opening 27, away from the machine.

The hollow bushings 17, 18, may be retained in place by any suitable means, but I prefer to use set screws such as I have shown for this purpose, and have provided in the frame 1 an opening whereby the set screw 28 may be reached from the exterior 50 of the machine.

These bushings 17, 18, may be removed and replaced by others having openings adapted for objects of different diameter, and the die 11 may be also removed and replaced by a die adapted for the straightening of objects of a different size. These 55 changes and substitutions may be made very readily by removing the cover plate 16.

Any one of a number of known methods 60 may be adopted so as to provide an adjustable mounting for the feed rolls 19, 20, but I prefer to secure them to their respective operating shafts by threaded nuts 29, readily removable, so that the feed rolls may 65 be removed, and replaced by others of dif-

ferent diameter, for use with objects of another size. Hand nuts 30, 30, are provided also in connection with these feed rolls, to provide for small variations in the sizes of the objects to be straightened, pressure being 70 applied to the upper bearing 31 of each pair, said bearings being capable of vertical adjustment for this purpose.

It will be obvious that a structure in which two dies are used,—one on each side 75 of the object 15,—with die hammers adapted to contact simultaneously with opposite rolls, will give precisely the same ultimate results as the structure disclosed in the accompanying drawings. In such a form one 80 die is recessed or cut away in the center, leaving the object supported by the shoulder extremities of the die; while the other and opposing die is cut away at its ends and is formed with a central projection 85 adapted to bend the unsupported object midway of the opposing die. Such a structure is found to give excellent results in practice.

It will be noted that the feed rolls 19, 19, 90 20, 20, are mounted in close proximity to the straightening head, and that the latter has been designed in such a compact form as to allow the material in exceedingly 95 short lengths to be fed into the mechanism and automatically drawn therefrom.

Having thus described my invention, I claim:

1. In a straightening machine the combination with a relatively fixed support for 100 the object to be straightened, of a rotating die-head, a radially-movable die mounted in said head, means to reciprocate said die at a uniform predetermined speed to and from the axis of rotation, and means to feed the 105 object to be straightened past said die.

2. In an automatic straightening machine and in combination, a main frame, an annular series of rolls mounted therein, a rotatable die-head mounted within and parallel with said series of rolls, a bending die 110 mounted for reciprocal radial movement within said die-head, a die-hammer mounted for reciprocal radial movement within said die-head adjacent to said bending die, means 115 to rotate said die-head so as to bring said hammer into successive contact with said rolls, and means to feed the material to be straightened at a uniform predetermined speed along the axis of rotation past said 120 die.

3. In a straightening machine, in combination, a rotating die-head, a radially reciprocating die mounted therein, means to rotate said die-head, means to reciprocate 125 said die at uniform, predetermined speed so as to deliver successive blows in the direction of the axis of rotation, and feeding devices operative along the axis of rotation of said die.

4. The herein described method of straightening an object which consists in subjecting said object to a series of bending blows delivered transversely of its longitudinal axis and around the periphery of said object at a uniform predetermined speed, and causing a uniform movement of the object being straightened in the direction of its longitudinal axis whereby the 10 blows contact with the surface of the ob-

ject in a spiral of substantially constant pitch.

In testimony whereof I hereunto set my hand this twelfth day of January, 1914, in the presence of two attesting witnesses.

FRANK HENRY SLEEPER.
